UNITED STATES PATENT OFFICE

139,201

DESIGN FOR A COSMETIC CONTAINER

Mary L. Yarcho, San Marino, Calif.

Application June 19, 1944, Serial No. 114,102

Term of patent 7 years

(Cl. D58—13)

To all whom it may concern:

Be it known that I, Mary L. Yarcho, a citizen of the United States and residing at San Marino, in the county of Los Angeles, State of California, have invented a new, original, and ornamental Design for a Cosmetic Container, of which the following is a specification, reference being had to the accompanying drawing forming part thereof, in which:

Fig. 1 is a perspective view of a cosmetic container showing my new design;

Fig. 2 is a front elevation thereof;
Fig. 3 is an end elevation thereof;
Fig. 4 is a plan view; and
Fig. 5 is a view in cross section as seen on the line 5—5 of Fig. 2.

I claim:

The ornamental design for a cosmetic container, as shown.

MARY L. YARCHO.
